UNITED STATES PATENT OFFICE.

ARTHUR H. GRUBER, OF LUDINGTON, MICHIGAN.

DESIGN FOR A TREAD FOR AUTOMOBILE TIRES.

Application filed April 14, 1922. Serial No. 1,741. Term of patent 3½ years.

To all whom it may concern:

Be it known that I, ARTHUR H. GRUBER, a citizen of the United States, residing at Ludington, in the county of Mason and State of Michigan, have invented a new, original, and ornamental Design for Tread for Automobile Tires, of which the following is a specification, reference being had to the accompanying drawing, forming part thereof.

Figure 1 is a plan view of a portion of a tread section of the tire, and

Figure 2 is a transverse section taken on the plane of the line 2—2 of Figure 1.

I claim:

The ornamental design for a tread for automobile tires, as shown.

In testimony that I claim the foregoing I have hereunto set my hand at Ludington, in the county of Mason and State of Michigan.

ARTHUR H. GRUBER.
